UNITED STATES PATENT OFFICE.

ONEY A. HONKANEN, OF PORTLAND, OREGON.

PROPELLER.

Application filed June 3, 1926. Serial No. 113,456.

This invention relates to improvements in propellers, and more particularly to propellers of a type of construction especially designed for the purpose of propelling boats, 5 but which also may be used successfully as propellers for aircraft.

It is the principal object of the invention to provide a propeller of the screw, or spiral, 10 type of construction which is more efficient than the ordinary type of propellers in that it requires less power to operate, provides more effective driving surface and is not required to be revolved at such speed as to lose effectiveness due to churning the water 15 in which it operates.

It is also an object of the invention to provide a propeller construction in which provision is made for the escape from between the propeller blades of dead water which, 20 ordinarily, impairs the efficiency of a propeller.

More specifically stated, the object of the present invention resides in the provision of a propeller comprising a single plate of 25 metal that is provided centrally and at its opposite ends, in its axial line, with hub bearings for mounting on a propeller shaft, and is formed in a half-turn spiral about the shaft. It is provided in its central body portion with openings for the escape of dead water which, otherwise, would retard action and decrease the efficiency of the propeller.

In accomplishing these and various other objects of the invention, I have provided the 35 improved details of construction, the preferred forms of which are illustrated in the accompanying drawings, wherein—

Figure 1 is a side elevation of a propeller embodied by the present invention.

Figure 2 is an end view of the same.

Figure 3 is a top view of device as shown in Figure 1.

Figure 4 is a cross section of the propeller.

Figure 5 is an end view of an alternative 45 construction.

Referring more in detail to the drawings—

1 designates, in its entirety, a propeller embodied by the present invention, which, 50 in its preferred form of construction, consists of a cast plate of metal that is formed about its longitudinal axis in a spiral turn. In the present construction, as illustrated, I have shown the plate as forming a half-turn spiral, but it is not intended that it be limited only to this extent as it may be desir-

able to make it more or less according to the particular use for which any certain propeller is to be put. At its opposite ends, and at the center of the plate, in axial alignment, 60 are hubs, or bearings, 2 for receiving the propeller driving shaft 3 which is keyed therein, as shown at 4 in Figure 2, and between the end bearings and the central bearing, the central body portions of the plate 65 are cut away providing elongated openings 5 for the escape of what may be termed dead water from between the propeller blades, which ordinarily would act to retard the propelling action and lessen the effectiveness 70 of the device. The surface area of the two halves of the propeller at opposite sides of the shaft 3, and also the area of the openings at opposite sides of the shaft, are equal 75 so as to provide a perfectly balanced construction and to insure against vibration in operation.

The propelling surfaces of the blades, preferably, are concave in cross section, as shown in Figure 4, so as to procure a better 80 grip, or driving hold, on the water in which it operates.

The propeller shown comprises two opposite side portions, or blades, 6 and 7 joined at their ends by the end portions 8 and 9 85 which are equipped with end bearings 2 for receiving the propeller shaft and the central connecting portion 10 which is equipped with the central bearing.

However, it is possible and may be desirable to provide propellers of this general character with any number of blades which would be determined by the particular use, or purpose, to which the propeller is to be put. Figure 4 shows a propeller having 95 three blades, this type being preferable in case the device is to be used as a fan or air blower.

Such propellers may be made in various sizes according to the propelling power desired to be obtained therefrom, and also in various proportions which would adapt them for use as propelling means for aircraft, or for fans or blowers of various kinds. For instance: A propeller for use on 100 an airship, or plane, could be greater in diameter in comparison to its length than the propeller herein illustrated.

Propellers of the above type have been found, by experiment, as compared to the 110 ordinary types of propellers, to be more effective in use, to provide more effective pro-

propelling surface, may be operated at fewer revolutions per minute without lessening the propelling speed, and do not churn the water with resultant loss of efficiency. The central openings provide for the escape of dead water from one side of the propeller to the opposite side where it then becomes active, or effective, to the other side of the propeller.

10 It is to be understood that various details of construction may be changed to adapt the device to various uses without departing from the spirit of the invention, and for this reason, I do not wish to be limited only to 15 the device as it is herein illustrated.

Having thus described my invention, what I claim as new therein and desire to secure by Letters-Patent, is:

1. A propeller of the character described 20 comprising a rectangular plate having the parts thereof lying at opposite sides of its

longitudinal axis formed in half-turn spirals directly opposite each other, said plate being provided for axial mounting on a propeller shaft and having its body portion cut away 25 to provide openings of equal area at opposite sides of the axis.

2. A propeller of the character described comprising a rectangular plate having the parts thereof lying at opposite sides of its 30 longitudinal axis formed in half-turn spirals directly opposite each other, said plate having hubs provided at its ends and centrally between its ends for receiving a propeller shaft, and having its central body portion 35 cut away equally at opposite sides of the axis between the end and center hubs to provide openings for the discharge of dead water from one side to the other.

Signed at Seattle, Washington, this 27th 40 day of May, 1926.

ONEY A. HONKANEN.
